CLAIM

The ornamental design for a bottle dispenser for earplugs, as shown and described.

DESCRIPTION

FIG. 1 is a front elevational view of a bottle dispenser for earplugs according to our new design;

FIG. 2 is a bottom plan view thereof;

FIG. 3 is a top plan view thereof;

FIG. 4 is a side elevational view thereof and with the other side being a mirror image;

FIG. 5 is a back elevational view thereof; and,

FIG. 6 is a back elevational view of an alternate embodiment thereof, the only difference residing in its vertical dimension.
